(57) CLAIM

The ornamental design for an apron-napkin article, as shown and described.

DESCRIPTION

FIG. 1 is a front perspective view of our apron-napkin article according to my new design showing a base section in a collapsed, folded position and an attached strap in a fully extended position;

FIG. 2 is a rear elevation view thereof;

FIG. 3 is a front elevation view thereof with the strap being partially shown;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front elevation view thereof with the base section in the collapsed, folded position and the attached strap in a folded position in which it is wrapped around the collapsed, folded base section;

FIG. 9 is a top plan view showing the base section in an open position with the attached strap in the fully extended position and the napkin in a completely folded state is shown inside the base section;

FIG. 11 is a right side elevation view thereof showing the base section in the open position with the attached strap, shown broken away for ease of illustration, in the fully extended position and showing partial unfolding and removal of a napkin that is contained within the base section, the left side elevation view being a mirror image;

FIG. 12 is a cross-sectional view taken along the line 12-12 of FIG. 9 illustrating the folded nature of the napkin contained within the base section and showing the strap broken away for ease of illustration; and,

FIG. 13 is a front perspective view showing the base section in the open position with the attached strap in the fully extended position and showing the unfolding and removal of the napkin that is contained within the base section.

The broken lines shown in the drawings illustrate portions of the apron-napkin article that form no part of the claimed design.
